Atty.

UNITED STATES PATENT OFFICE.

EDWARD R. PENROSE, OF LOGANSPORT, INDIANA.

LIFTING-JACK.

1,377,026.

Specification of Letters Patent.

Patented May 3, 1921.

Application filed August 17, 1920. Serial No. 404,138.

To all whom it may concern:

Be it known that I, EDWARD R. PENROSE, a citizen of the United States of America, and a resident of Logansport, in the county 5 of Cass and State of Indiana, have invented certain new and useful Improvements in Lifting-Jacks, of which the following is a specification.

This invention relates to lifting jacks 10 and has for its object the production of an inexpensive device of this character which is simple in construction and easily operated.

The invention consists primarily of novel 15 mechanism for rotating the lifting screw in its nut, said mechanism being mounted directly upon the revoluble lifting screw.

The invention further consists in the means employed for securing a revoluble 20 head to the upper end of the lifting screw.

The invention further consists in providing the screw-operating mechanism with a pivoted socket member to receive an actuating lever whereby the operating mechanism 25 may be actuated with the actuating lever at various angles to said mechanism.

The invention further consists in certain 30 novel features of construction and arrangement of parts which will be understood readily by reference to the description of the drawings and to the claims hereinafter given.

For the purpose of illustrating the invention, one preferred form thereof is illustrated in the drawings, this form having been found to give satisfactory and reliable results although it is to be understood that the various instrumentalities of which the invention consists can be variously arranged 40 and organized and the invention is not limited to the precise arrangement and organization of these instrumentalities as herein shown and described, except as required by the scope of the appended claims.

45 Of the drawings:

Figure 1 represents a vertical section of a lifting jack embodying the principles of the present invention, and

50 Fig. 2 represents a horizontal section of same on line 2, 2, on Fig. 1.

Similar characters indicate like parts throughout the several figures of the drawings.

55 In the drawings, 10 is a base member provided with a handle 11.

Formed in the upper end of the base 10 is a nut 12 in which is mounted a revoluble lifting screw 13.

The upper end of the lifting screw 13 is provided with the cylindrical bearing surfaces 14 and 15 between which is a flat-sided, preferably hexagonal, portion 16.

This hexagonal portion 16 has fitted thereto, a ratchet 17, secured to the screw 13 by means of a pin 18 which prevents end movement of said ratchet on said screw 13.

Fitted to the cylindrical bearing surface 15 is a plate 19 and fitted to the cylindrical bearing surface 14 is a similar plate 20.

The parts of said plates 19 and 20 radiating from the screw 13 have secured thereto a member 21 interposed between said plates.

These plates 19 and 20 and member 21 are fastened together by means of bolts 22 and nuts 23.

This construction facilitates the assembling of the device but if desired the plates 19 and 20 and member 21 may be formed integral.

The member 21 has at its outer end an ear 24 having a bolt 25 horizontally disposed therein which bolt 25 projects through the bifurcated end 26 of a member 27 having a socket 28 in the outer end thereof adapted to receive the end of any usual actuating lever.

By means of this pivotal connection, when it is desired to operate the jack the socketed member 27 may be moved vertically and at an angle to the member 21 as indicated 90 in dotted lines in Fig. 1 of the drawings.

This is of considerable advantage as when the jack is in a low position it obviates the necessity of the operator stooping while manipulating the operating mechanism.

The plates 19 and 20 have disposed therein a pin 29 forming a pivot for the double-acting pawl 30.

The outer end of the pawl 30 is V-shaped and is adapted to be engaged by the V-shaped end of the locking bolt 31.

This bolt 31 is mounted in a socket 32 in the member 21 and is pressed outwardly by means of the spring 33 in the rear thereof.

The bolt 31 is provided with a groove 34 105 extending longitudinally thereof and coacting with a pin 35 threaded to the member 21.

This pin 31 limits the movement of the bolt 34 in opposite directions and prevents 110

the rotation thereof so that the V-shaped end of said bolt 31 is always in position to coact with the V-shaped outer end of the pawl 30.

5 In Fig. 2 the pawl 30 is shown locked in position to move the operating device in the direction of the arrow *a* on said figure.

When, however, it is desired to move the operating mechanism in the opposite direction, the pawl 30 may be snapped past the V-shaped end of the lock bolt 31 and said pawl 30 will then be locked in position to attain a reverse movement of the lifting screw 13.

15 Above the plate 5, the screw 13 is provided with an enlarged end 36 having an annular groove 37 in the upper face thereof.

This groove has disposed therein a plurality of anti-friction members such as the 20 balls 38 shown in Fig. 1 of the drawings.

Resting upon the balls 38 is a revoluble head 39 having an apron 40 extending downwardly and surrounding the enlarged end 36 of the screw 13.

25 The screw 13 is also provided with a central, upwardly extending cylindrical projection 41 fitted to a cylindrical hole in the head 39.

The upper end of the head 39 is provided 30 with a shouldered depression 42 in which and against the shoulder of which is positioned a plate 43 secured to the reduced end 41 of the screw 13 by means of a securing member 44.

35 The head 39 is provided with a cap 45 secured thereto by means of screws 46, said cap closing the depression 42.

The plate 43 in the depression 42 prevents the head from being displaced from 40 the screw 13.

The upper face of the cap 45 is serrated as indicated at 47 and this face engages the work to be lifted when the work is mounted upon the cap 43 and as the load is being 45 lifted the head 39 will be prevented from rotating while the operating mechanism is effecting the rotation of the screw 13 in the nut 12.

This makes a very simple construction of 50 lifting jack well adapted for certain uses, is inexpensive to make, and easily operated.

It is believed that the operation and many

advantages of the invention will be readily understood without further description.

Having thus described my invention, I 55 claim—

1. The combination of a base provided with a non-revoluble nut; a lifting screw for said nut having formed integral therewith near the upper end thereof a flat-sided portion and cylindrical bearing surfaces on opposite sides thereof of a greater diameter than that of said screw; a ratchet fitted to said flat-sided portion; a pin extending through said ratchet and screw; and screw 65 operating mechanism having bearings on said cylindrical bearing surfaces and adapted to be oscillated about the axis of said screw.

2. The combination of a base provided 70 with a non-revoluble nut; a lifting screw for said nut having formed integral therewith a cylindrical head, a cylindrical bearing surface beneath said head having a diameter less than that of said head, a portion beneath said bearing surface having a plurality of flat sides, and another cylindrical bearing surface beneath said flat-sided portion and having a diameter less than that of the first-mentioned bearing surface and 80 greater than that of said screw; a ratchet fitted to said flat-sided portion; means preventing end movement of said ratchet relatively to said screw; and screw-operating mechanism having bearings on said cylindrical bearing surfaces and adapted to be oscillated about the axis of said screw. 75

3. The combination of a base provided with a non-revoluble nut; a lifting screw for said nut having formed integral therewith a 90 cylindrical head and two cylindrical bearing surfaces beneath said head and separated by a flat-sided peripheral portion; a ratchet fitted to said flat-sided portion; means preventing end movement of said 95 ratchet relatively to said screw; a bifurcated member straddling said ratchet and having bearings for said separated cylindrical bearing surfaces; and a spring-pressed pivoted pawl mounted on said bifurcated member 100 and coacting with said ratchet.

Signed by me at 746-7 Old South Bldg., Boston, Mass., this 12th day of August, 1920.

EDWARD R. PENROSE.
